US00D892310S

(12) **United States Design Patent** (10) **Patent No.:** **US D892,310 S**
(45) **Date of Patent:** **** Aug. 4, 2020**

(54) **DEVICE FOR SAMPLE COLLECTION**

(71) Applicant: **Drawbridge Health, Inc.**, Menlo Park, CA (US)

(72) Inventors: **Brett L. Jordan**, San Francisco, CA (US); **Masao Drexel**, Mountain View, CA (US); **Alicia Jackson**, Menlo Park, CA (US); **Kara Juneau**, Palo Alto, CA (US); **Dagmar Beyerlein**, San Francisco, CA (US)

(73) Assignee: **Drawbridge Health, Inc.**, Menlo Park, CA (US)

(**) Term: **15 Years**

(21) Appl. No.: **29/655,964**

(22) Filed: **Jul. 9, 2018**

Related U.S. Application Data

(63) Continuation of application No. PCT/US2018/013223, filed on Jan. 10, 2018.

(57) **CLAIM**

The ornamental design for a device for sample collection, as shown and described.

DESCRIPTION

FIG. 1 corresponds to a front view of the device for sample collection;

FIG. 2 corresponds to a rear view of the device for sample collection;

FIG. 3 corresponds to a top view of the device for sample collection;

FIG. 4 corresponds to a bottom view of the device for sample collection;

FIG. 5 corresponds to a left view of the device for sample collection;

FIG. 6 corresponds to a right view of the device for sample collection;

FIG. 7 corresponds to a first perspective view of the device for sample collection from the front;

FIG. 8 corresponds to a second perspective view of the device for sample collection from the rear; and,

FIG. 9 corresponds to a third perspective view of the device for sample collection from the bottom.

1 Claim, 9 Drawing Sheets
